SEAT ATTACHMENT FOR WATER CLOSETS

William C. Groeniger, Columbus, Ohio, assignor
to John B. Pierce Foundation, New York, N. Y.,
a corporation of New York

Application June 7, 1935, Serial No. 25,474

7 Claims. (Cl. 4—236)

My present invention relates to plumbing devices, and more particularly to an improved seat attachment for defecators and the like.

My invention is designed primarily for use in connection with a bracket type of defecator, such as is disclosed and claimed in my co-pending application, Serial No. 749,069, filed Oct. 19, 1934, but is adapted for use in connection with the usual and ordinary type of defecator, and may be substituted for a seat attachment of any existing type of defecator.

In carrying out my invention, I utilize the means for associating the defecator seat and defecator cover with a defecator attached to a wall or other supporting element. The functions above referred to are performed by the same means but such means are independently adjustable with respect to each other.

The principal object of my invention therefore, is an improved seat attachment for defecators and the like.

Another object of my invention is a combined defecator securing means and seat attachment means.

Another object of my invention is an improved seat attachment means for defecators and the like, wherein an adjustment is provided for adjusting the position of the associated seat and cover relative to the defecator.

Other objects and novel features of the construction and arrangement of parts comprising my device will appear as the description of the invention progresses.

In the accompanying drawings:

Fig. 1 is a perspective view showing my device in position with respect to a defecator and supporting wall and illustrating the means for supporting the defecator seat and cover.

Fig. 2 is a sectional plan view on the line 2—2 of Fig. 1.

Fig. 3 is a perspective view of a portion of my device showing the defecator supporting nut and pivot means for the defecator seat and cover in axial alignment with, but separated from each other.

Fig. 4 is a sectional elevation on line 4—4 of Fig. 2 and

Fig. 5 is a plan view partly in section showing a modified form of my invention.

Referring to the drawings;

10 designates a section of a wall forming one of the enclosing elements of a bathroom and comprising, essentially the wall 11 proper, cement facing 12 and tiling 13. 14 designates a wall or bracket type of defecator having formed integral

therewith a lower vertical plate or apron 15 and an upper vertical plate or apron 16 provided with perforations through which pass the means for securely mounting the defecator 14 to the wall 10. The fastening means which pass through the vertical wall 15 do not concern my present inventions and therefore will not be described in detail.

The wall 10, in the rear of the vertical apron 16, is drilled or otherwise perforated, as indicated by reference numeral 17, to allow passage there-through of bolts 18. Preferably two of such bolts are provided and the heads 19 of such bolts are multi-sided, while the ends of such bolts which extend outward from the wall 10 through perforations 20 in the vertical wall 16 of the defecator 14, are threaded as indicated by the reference numeral 21.

Lying adjacent to the face of the wall 10, remote from the tiling 13, are spaced channel members 22, and such channel members may consist merely of vertical risers, as shown in the drawings, or may be provided with a portion extending at right angles thereto and extending under, preferably, the floor of the bathroom, such extending portion being rigidly secured to said floor. Such construction enables me to use a relatively light form of wall 10, as the defecator 14 is then substantially supported on the channel member 22. Such a construction, however, is not essential and does not affect my present invention. The channel members 22 are perforated as shown in Fig. 2 to allow passage of the bolts 18, and such perforations are elongated as shown in Fig. 1 to allow relative movement of the bolts 18 longitudinally of the channel members 22, and also to enable me to house the multi-sided heads of such bolts 18 thereof by the member 23.

Screwing onto the threaded end 21 of the bolts 18 is a nut 24, provided at its forward end with a cylindrical recessed chamber 25, and provided at its rear end with a plurality of faces which permit the nut 24 to be screwed onto the threaded end 21 of the bolts 18 by means of the usual wrench.

Referring to Fig. 2, it will be noted that when the defecator 14 is placed in position against the tiled surface of the wall 10, and with the threaded ends of the bolts 18 protruding through perforations 20, that a washer 27 is placed between the nut and the finished face of the vertical wall 16 of the defecator. Nut 24 is then screwed onto the bolt 18 until the defecator 14 is firmly positioned on the wall 10. Because of the elongated perforations in the channel members 22, and because of the clearance between the bolts 18 and

the perforation 20 in the vertical wall 16, it is obvious that a considerable lateral and vertical movement of the defecator 14 is permitted in order that the same may be properly positioned 5 on the wall 10.

Under the conditions of assembly as set out above, it is noted on reference to Fig. 2 that the threaded end 21 of the bolts 18 extend outward beyond the limits of the cylindrical portion of the nut 24 and on such extending portion is adapted 10 to be screwed the cylindrical members 29, said members 29 being, of course, internally threaded to cooperate with the threads 21. The diameter of the cylindrical members 29 is such that same is 15 capable of sliding engagement into the cylindrical chamber 25 of the nut 24. The forward or outer ends of the cylindrical members 29 have formed integrally therewith the substantially rectangular and flat sided bearing member 30, such bearing member being provided with a transverse passage 31, extending therethrough. The 20 passages 31 in the bearing members 30 are brought into alignment with each other, as clearly shown in Fig. 2, and when thus aligned are 25 adapted to receive a shaft 32, such shaft being threaded at each end.

33 designates a defecator cover provided with an integral rearward extension 34 which in turn is provided with a transverse passage in 30 which is mounted, a metallic bearing sleeve 35 having an internal diameter slightly greater than the external diameter of the shaft 32. The width of the rearward extension 34 is slightly less than the distance between adjacent 35 faces of the bearing members 30, on the cylindrical members 29 above referred to.

With such construction it is obvious that the defecator seat 33 may be mounted on the shaft 32 and rotation thereof is permitted about such 40 shaft as a center. 36 designates the seat cover provided at its rear-end with spaced and rearwardly extending lugs 37. The distance between the lugs 37 is slightly more than the distance between the opposite outer faces of the bearing members 30. Such lugs 37 are provided with 45 aligned perforations, in each of which is securely fastened a metallic bearing sleeve 38. Such bearing sleeves 38 have an inner diameter slightly greater than the outer diameter of shaft 32, and such shaft 32, as will be noted upon inspection of 50 Fig. 2, has the threaded ends thereof extending laterally outward beyond the lugs 37. It is obvious therefore from the above construction, that the seat cover 36 is permitted a rotary movement 55 about the shaft 32 as a center. Screwing onto the threaded ends of the shaft 32 are cap nuts 39, there being washer 39 interposed between the cap nuts 38 and the outer faces of lugs 37.

60 On the seat cover 36, between the adjacent faces of the bearing members 30, is formed an integral rearward extension 41 which forms a finish for the seat cover 36. Also in conjunction with the lugs 37 of recess 42, such extension 41 acts 65 as a stop to limit the upward and rearward rotary movement of the seat cover 36. Preferably the depth of the recesses 42 is so proportioned as to prevent the seat cover 36 from rotating rearwardly far enough to strike against the tiling 70 13 on the wall 10.

As ordinarily the defecator 14, and the vertical wall members 15 and 16 are formed of vitreous material and integral with each other and therefore it is impracticable from a commercial point 75 of view to manufacture the same exactly to size,

and because of the mechanical difficulty of building an accurately faced wall 10, it is necessary to provide not only adjustment in the setting of the defecator 14 on the wall 10, as above described, but also to provide means for adjusting 5 the seat 33 and seat cover 36 with respect to the defecator 14. Such adjustment is provided by means of the cylindrical members 29 above described, and is obtained by threading the cylindrical members 29 further in or out of the respective cylindrical chambers 25. It is obvious that I am thus enabled to vary the relative position, within reasonable limits, of the seat 33 and seat cover 36 on the defecator 14.

Referring now to Fig. 5, wherein is shown a 15 modification of my invention, I have arranged clamping nuts 43 for clamping the defecator 14 onto the wall 10 by means of the bolts 18, with a multi-sided portion and forwardly extending cylindrical section 44. Associated with such nuts 20 43 are the bearing members 45, the rearward ends of which are provided with cylindrical recesses 46 for enclosing and permitting longitudinal movement thereof with respect to the cylindrical portions 44 of the nuts 43.

On the forward end of each of the members 45 are bearing members 47. Associated with each of the bearing members 47 and extending laterally therethrough are bearing shafts 48, provided at each end with a threaded portion and passage 30 to receive the cap nuts 49. In this modification of my invention the seat 50 has formed integral therewith and at the rear end thereof, bearing lugs or ears 51, such lugs or ears 51 being spaced apart from each other and adapted to have 35 passed through perforations therein the shaft 48. The seat cover 52 has formed integral therewith and at the rear end thereof, lugs or ears 53 spaced apart from each other and provided with perforations through which may pass the shaft 40 48. In this form of my modification, the lugs 53 of the seat cover 52 are so formed as to provide a stop portion 54. Such portion 54 striking against the top of the bearing members 47 will limit the rearward pivotal move of the seat cover 45 52 about the shaft 48.

Preferably the seat 33 or the seat 50 is adapted to be enclosed by the special form of seat cover 36 or 52 respectively, but as such seat and cover form no part of my present invention they have 55 not been described in detail. For a full disclosure of the details of construction of such a seat and seat cover, reference is had to my co-pending application Serial No. 25,365 filed June 7, 1935.

While I have necessarily shown and described 55 the preferred embodiments of my invention, somewhat in detail, it is to be understood that I may vary the size, shape and arrangement of parts comprising my improved structure within 60 relatively wide limits without departing from the spirit of the invention.

I claim:

1. In combination with a defecator bowl and a seat and cover therefor, of means for securing the defecator bowl in position with respect to a vertical support, and for adjustably mounting said seat and cover on the top of the defecator bowl, said means including a pair of threaded bolts and a pair of threaded members recessed at one end, for securing the defecator bowl on the vertical support, and with the threaded bolts extending 65 forwardly and horizontally outward from the vertical support and arranged above and parallel to upper surface of the defecator bowl, and bearing members for the seat and cover movable lon- 70 75

itudinally of the threaded bolts independently of the threaded members, said bearing members having their ends housing within the adjacent ends of the threaded members.

5. 2. In a device of the kind described, the combination of a defecator bowl adapted for mounting on a wall and having an upwardly extending flange at the rear thereof with a horizontal aperture therein, a bolt extending through the wall 10 and having its threaded end extending through the horizontal aperture of the flange, a threaded member screwing onto the extending threaded end of the bolt for securing the defecator bowl in position on the wall, said threaded end of the 15 bolt extending outwardly from the end of the threaded member remote from the wall, a recess formed in the end of the threaded member remote from the wall, a member housing in said recess and screwing onto the extending end of 20 the bolt, a horizontal bearing formed in said member, and a defecator seat and cover pivotally mounted in said bearing.

3. In combination with a defecator bowl and a seat and cover therefor, of means for securing the 25 defecator bowl in position on a vertical support and for adjustably mounting said seat and cover on the top of the defecator bowl, said means including a pair of threaded bolts and a pair of threaded members cooperating to secure the defecator 30 bowl on the vertical support and with the threaded bolts arranged substantially parallel to each other and extending forwardly and horizontally outward from the vertical support and arranged above and substantially parallel to the 35 upper surface of the defecator bowl, and bearing means for said seat and cover movable longitudinally of the threaded bolts independently thereof and of each other, whereby adjustment of the seat and cover is provided with respect to 40 the defecator bowl.

4. In combination with a defecator bowl and a seat and cover therefor, of means for securing said defecator bowl in position on a support and for pivotally mounting the seat and cover in position with respect to the top surface of the 45 defecator bowl, said means including a pair of threaded bolts engaging with the supports and passing through spaced perforations in the defecator bowl structure and extending outwardly 50 parallel to each other and parallel to, but spaced above, the top surface of the defecator bowl, threaded members screwing onto the threaded bolts and securely attaching the defecator bowl to the support, said threaded members at their 55 outer end being recessed, and bearing members

for pivotally mounting the seat and cover in position with respect to the defecator bowl, and movable longitudinally on the threaded bolts and housing partly within the recesses, said bearing means being each movable independently of the 5 other along their respective threaded bolts whereby the seat and cover may be adjusted with respect to the top surface of the defecator bowl.

5. In combination with a defecator bowl and a seat and cover therefor, of means including a 10 pair of threaded bolts and a pair of threaded members for securing the defecator bowl in position against a wall or other supporting structure and with the threaded bolts extending horizontally outward from the wall above and parallel to the upper surface of the defecator bowl, a recess in the outer end of the threaded members, and bearing means for the seat and cover associated with the threaded bolts and housing partly within the recesses in the threaded members, said bearing members being movable along the respective bolts independently of each other and independently of the threaded members, whereby adjustment of the seat and cover is provided with respect to the top of the defecator 25 bowl.

6. In combination with a defecator bowl and a seat and cover therefor, of means including a 30 pair of threaded bolts and a pair of threaded members for securing the defecator bowl in position against a wall and with the threaded bolts extending horizontally outward from the wall above, and parallel to, the upper surface of the defecator bowl, and bearing means for the seat and cover movable longitudinally of the threaded 35 bolts and independently of the threaded means.

7. In a combined mounting for a defecator bowl and a seat and cover therefor, the combination of a headed and threaded bolt adapted to have its threaded portion extend through perforations in a wall and in the defecator bowl structure, an internally threaded member screwing onto the threaded end of the bolt and holding the defecator bowl in set position on a wall or other support, a recess formed in said internally 45 threaded member of the end remote from the wall, a member internally threaded at one end and provided at its other end with a horizontal bearing adapted to pivotally receive a defecator seat and cover, said member adapted to be moved 50 longitudinally of the threaded end of the bolt to adjust the seat and cover relatively to the top of the defecator bowl.
